(57) **CLAIM**

The ornamental design for a stucco lifter, as shown and described.

DESCRIPTION

FIG. 1 is a top edge view of a stucco lifter;
FIG. 2 is a front view thereof;

FIG. 3 is a right edge view thereof; the left side view being a mirror image;

FIG. 4 is a bottom edge view thereof;

FIG. 5 is a back view thereof; and,

FIG. 6 is an isometric view thereof.

The broken lines in FIGS. 2, 5, and 6 illustrate unclaimed environmental structure which forms no part of the claimed invention.
